SHOE FITTING APPARATUS

Howard V. S. Mott, Cranston, R. I.

Application February 6, 1937, Serial No. 124,419

15 Claims. (Cl. 250—59)

This invention relates to X-ray shoe fitting apparatus; and has for one of its objects to provide means for use therewith adapted to accurately locate and delimit the extreme borders of the foot and also to indicate and determine the exact size measurements of the functioning foot for correct fitting in footwear.

Another object of the invention is to provide means which is interposed between a fluorescent screen and the source of X-rays and capable of casting shadows of a reticulated arrangement on the screen with the aid of X-rays in which the arrangement of shadow lines is such as to determine the exact size measurements of a foot either when placed within a shoe during a trial fitting or without the shoe, to show the length of toes, the length of metatarsal bones, and extreme foot width when in weight bearing.

Another object of the invention is to provide a flooring support for a foot having a foot receiving surface permeable to X-rays upon or below which are arranged elements opaque to X-rays and capable of casting shadows which are visibly differentiated in a fluorescent screen from the various permeable parts of the supporting floor, shoe and foot structures to determine foot and shoe size indications for correct shoe fitting.

Another object of the invention is to provide a device of the above character which is simple and inexpensive to construct and capable of accurately showing the extreme width and length measurements of the foot and the relation of the shoe to the foot with the aid of Roentgen or X-rays for correct shoe fitting.

With these and other objects in view, the invention consists of certain novel features of construction, as will be more fully described, and particularly pointed out in the appended claims.

In the accompanying drawing:

40 Fig. 1 is a diagrammatic perspective view, partly in section and dotted outline, of a foot measuring device made in accordance with my invention and showing a foot and shoe in operative position relative to a fluoroscopic screen and an X-ray tube;

45 Fig. 2 is a transverse sectional view taken approximately on the line 2—2 of Fig. 1 and showing the top of my foot measuring device with the foot represented in a proper position to be measured for size and fit;

50 Fig. 3 is a cross sectional view taken on the line 3—3 of Fig. 2;

55 Fig. 4 is an enlarged fragmentary sectional view taken on the line 4—4 of Fig. 2;

Fig. 5 is a sectional view taken on the line 5—5 of Fig. 4;

Fig. 6 is an enlarged fragmentary sectional view of my foot measuring device, diagrammatically illustrating the relative position of the foot and shoe with respect to the grid structure of my device; and

Fig. 7 is a cross sectional view illustrating a modified form of my invention.

In one known method of shoe fitting as practiced in some of the shoe stores there is employed an apparatus whereby a foot during a trial fitting of a shoe of supposedly the correct size is exposed to beams of Roentgen or X-rays, and an observation made of the shadows of the foot and shoe structures which are cast upon a fluorescent screen which is arranged above the shoe, in an effort to determine the location and degree of fitting of the foot relative to the shoe. However, the results obtained from the use of such prior 10 apparatus have not been satisfactory since in such prior X-ray apparatus there is no convenient or effective means of either determining the exact foot and shoe measurements in ratio to shoe 15 width or size, or of locating the exact positions of the marginal portions of the foot including the superficial tissues surrounding the bone structure when in place within the shoe. Consequently, the results obtained therefrom are uncertain and misleading due to the fact that the shadows which 20 are thrown on the fluorescent screen and representing the outer borders of the fleshy tissues of the foot and the contiguous parts of the shoe upper are not capable of being visibly differentiated 25 from each other but present a confused or indistinct appearance since such parts of the foot and shoe structures are not of sufficiently different permeabilities to the Roentgen or X-rays to 30 show as strong contrasting shadows in the fluorescent screen.

In order to improve the performance of this prior X-ray apparatus so as to obtain an accurate determination of the exact location and necessary measurements in length and width of the position of the functioning foot within a trial shoe 45 and also to give a correct indication when correct shoe fitting is attained, there is shown and described in my Patent No. 2,109,780, granted March 1, 1938, an improved form of shoe construction wherein a plurality of indicator markers composed of a material opaque to Roentgen or X-rays are disposed within or upon the structure of the shoe upper and above the sole member thereof at the extreme outer borders of the foot for locating 50 the positions of the latter by means of shadow 55

outlines of the markers which are cast upon a fluorescent screen and showing in strong contrast and clearly distinguishable from the shoe and foot structures in the line of vision in the field 5 of the X-rays. In order to supplement my above described shoe construction and for the purpose of rendering practicable the prior X-ray apparatus, I further provide means to assist in locating and measuring the exact size of a foot when fitting 10 a shoe, either of the above described construction or an ordinary shoe, in which my measuring means is of a character and so constructed as to cast shadows of a generally retiform or reticulated pattern on a screen, fluorescent surface, 15 sensitive plate or suitable image receiving surface wherein the extreme length and width measurements of the foot and shoe will be readily located and delimited, either by falling between respective size indicating shadow lines projected upon the 20 image receiving surface or by being coincident with a single shadow line thereon extending either transversely or longitudinally of the foot and shoe under observation and cast by the X-ray beam on the fluoroscopic screen; and in order to accomplish this result I form said means of a material 25 opaque to X-rays and of a character to provide a plurality of dense linear areas in the path of the actinic rays and so arranged that the shadows cast thereby on the fluorescent screen will form 30 rows of shadow lines which correspond with the usual length and width distances of recognized standards of foot and shoe measurements and so marked by opaque substances whereby the extreme lateral and longitudinal displacements of 35 the foot in relation to a trial shoe may be accurately determined and measured; and to this end, it is found of advantage to provide a support or base for a foot having a suitable foot receiving surface which is permeable or transparent to X- 40 rays in which the measuring and locating means comprises a plurality of separate parallel slender elongated elements disposed either upon or below the level of the foot receiving surface of said support, and in the latter instance they may be either 45 incorporated within or located exteriorly of the foot support; and the following is a more detailed description of the present embodiment of this invention, illustrating the preferred means by which these advantageous results may be accomplished. 50

With reference to the drawing, the numeral 10 designates a support or base for one or both feet and having a generally plane foot receiving surface 11 on which the person having his feet 55 fitted to shoes stands during the trial fitting and X-ray examination, the support 10 being interposed between an X-ray device 12 and a fluorescent screen 13. The foot support 10 may be constructed of suitable material which is permeable to Roentgen or X-rays, such as aluminum, 60 wood, paper, pasteboard or other material capable of being readily penetrated by the actinic rays, and also may be made either as a solid or of a laminated construction, as desired. As illustrated in Fig. 1, the screen 13 may be mounted in a suitable housing, such as shown in the patent to Lowe, No. 1,614,988 of January 18, 1927, in order to provide a suitable viewing chamber for enabling an observer to view the shadow 65 images cast upon the fluoroscopic screen 13.

In order to assist in determining the exact measurement to a shoe of a foot when placed within a trial shoe and to obtain an accurate measurement of the size and width of the functioning foot therein, I have provided measuring 70

means either on or within the support 10 and formed of a material or substance opaque to X-rays. The measuring means may also be disposed either between the foot receiving surface 11 of the support 10 and the X-ray device 12, 75 or it may be provided upon or embodied in the top of the foot receiving surface 11 itself. However, in my preferred construction, as shown in Figs. 2 to 6, my measuring means consists of a plurality of rows of parallel wires, rods or bars which extend transversely and longitudinally of the support 10. The wires, rods or bars 15 and 16 respectively, may be formed of any suitable dense material, as for example a metal such as iron, copper, lead, or other suitable substances such as vulcanized rubber, which are capable of obstructing the passage of X-rays to a degree sufficient to produce strong shadows on the screen and visibly distinguishable from the permeable structures of the foot and shoe. It is 20 also feasible to utilize a construction in which the foot receiving surface 11 of the support 10 is provided with a ruled appearance having rows of crossing lines upon or cuts (see Fig. 7) formed in the top surface thereof. In either instance, 25 the lines or cuts will contain a substance which is opaque to X-rays.

In the specific embodiment of my invention, as illustrated in Figs. 2 to 6, the support 10 is shown as being of a laminated construction in 30 which two tiers of rows of wire elements 15 and 16 respectively are disposed between the several layers of the support, one group of rows of parallel elements 15 being placed between the top and intermediate layers of the support while the 35 other group of rows of parallel elements 16 are interposed between the intermediate and the base layers of the support. It will be understood, of course, that the parallel rows of elements 15 may run either transversely or longitudinally 40 of the support, in which instance, the elements 16 which are also in a parallel relationship with each other will be arranged to run cross-wise of the elements 15, and preferably at right angles thereto, thus casting a network of shadow lines 45 upon the fluorescent screen 13 upon exposure to the action of X-rays. As a further feasible construction which may be utilized, a wire screen may be interposed between the fluorescent screen 13 and the source of X-rays in lieu of the arrangement of wires 15 and 16, and it may be embedded either in the support 10 or exteriorly 50 disposed between the bottom of the latter and the X-ray device 12. However, in all instances, the arrangement is such that the spacing between the adjacent rows of parallel wires 15 and 16, or those of a metal screen if such is used, corresponds to the usual distances of recognized 55 standards of foot and shoe measurements.

In order that a determination of the positions 60 of both feet may be observed during a single X-raying operation, the support 10 is provided with a central partition 20 which divides the foot receiving surface 11 into halves, and the measuring elements 15 and 16 are disposed on each side 65 of the partition 20 in order to accommodate right and left foot measurements. As shown in Fig. 2, the partition 20 extends lengthwise of the support 10 and disposed at one end of the latter is a heel member 21 in the form of a 70 plate which extends transversely of the support 10 so as to provide a base or datum line from which the length measurements of the feet are made. The heel member 21 may either be made rigid and upstanding on the support 10 or it may 75

be pivoted thereon, as shown in Figs. 1 and 2, for swinging movement into and out of a vertical and contiguous position with respect to the partition in order to provide for ingress and egress of the foot or feet from the shoe fitting apparatus. Also, the height of the heel member 21 when in an operative position is such that its inner top edge 22 will reach to substantially the middle portion of the end of the heel of the shoe upper or substantially to a point thereof of maximum displacement in a vertical plane, as shown in Fig. 1. A suitable locking device 23 may be provided to releasably hold the heel member 21 in an operative position.

In order to accommodate for the normal thickness of a shoe sole, the partition 20 extends vertically upwardly to a point slightly above the average thickness of an ordinary shoe sole, at which position the partition 20 is provided with flanged portions 24 which are co-extensive therewith and extend transversely outwardly from the longitudinal side faces of the partition 20 to provide a shelf of T-shape and extending over the inner margins of the soles of each foot. The outer side faces of the flanges 24 are substantially in alignment with the transverse medial plane of the feet and provide an abutment therefor at the first metatarso-phalangeal joints thereof and form a datum line on each side of the partition 20 from which the extreme width of foot is measured to the superficial tissues around the fifth metatarso-phalangeal joint. The outer side faces of the flanged portions 24 also provide a right angle corner with the inner face of the heel member 21 for receiving the heel portion of the shoe upper. Thus, the inner border of the shoe upper or the skin over the first metatarso-phalangeal joint of each foot rests against an outer face of the flanged portions 24 and lie on a straight line aligned with the inner margin of the heel upper and making a right angle with the plane of the heel member 21 when normal to the partition 20 and forming the lateral datum line of measurement for shoe length. As shown in Fig. 2 the wires or rods 15 run laterally across the support 10 and their distances are measured from the inside face of the heel member 21 when the latter is at right angles to the partition 20 for correct foot and shoe width. Also, in Fig. 2, the wires or rods 16 are shown as extending in a longitudinal direction of the support and their distances are measured in a transverse direction from the outside edge of each of the flanged portions 24.

In order to accurately locate the inner extreme margins of the foot contour when subjected to the action of X-rays I make either the outer side edges of the flanged portions 24 or all of the latter, and including the partition 20 if so desired, of a material impermeable to X-rays and capable of being easily seen in the fluorescent screen where the measurements begin. As shown in Fig. 3, I have provided each of the longitudinal side edges of the flanged member 24 with a binding edge 25 composed of a dense material opaque to X-rays, such as vulcanized rubber or metal, as for example, copper, iron, steel or lead.

In order to assist in locating the extreme inner and outer dimensions of the foot, I preferably employ the shoe structure as described and claimed in my Patent No. 2,169,780, which construction is illustrated in Fig. 6 of the drawing and consists of a pair of transversely opposed index markers 26 and 27 which are opaque to

X-rays and arranged on or within the material of the shoe upper and so placed as to be against the superficial tissues of the foot at the first and fifth metatarso-phalangeal joints thereof to move laterally therewith during the action of the foot within the shoe and thus cast their shadows on the screen in relation to the fixed longitudinal shadow lines which are thrown thereon by the wires 16 wherein the latter serve to delimit and determine the extreme width of the foot contour by coincidence therewith or by lateral displacement between the shadow lines. The shoe structure may further be provided with an opaque index marker 28 which is placed in the toe cap above the shoe sole at the correct distance from the distal ends of the toes for correct fitting of the foot and thus show between a pair of parallel shadow lines of the wires 15 or be brought into coincidence or alignment with the shadow line cast by one of the transverse wires 15 to thus give an accurate measurement of the foot length beyond the ends of the toes during the trial fitting.

It will of course be understood that the elements 15 and 16 will be suitably marked with characters designating length and width measurements of the usual recognized distances of foot and shoe measurements, as for example one-sixth of an inch. Consequently, these size characters will be made of a material or substance opaque to X-rays and capable of showing up prominently on the fluorescent screen under the action of X-rays.

As shown in Fig. 7 a modified form of the invention comprises a support 30 having a foot receiving surface 31 which is provided with a plurality of parallel lines 33 formed by cutting parallel grooves into the top surface portion of the support 30, while other lines 34 are disposed at right angles to the lines 33 to intersect the same and are similarly cut in the support, the lines 33 and 34 being spaced in the same ratio as the foot and shoe size measurements for width and length of last and the cuts or grooves then are filled or painted with a material containing a substance, such as lead, which is opaque or impermeable to X-rays.

It will thus be apparent in view of the above disclosure that my invention will facilitate the determination of correct foot and shoe sizes with or without shoes on the feet of the person being fitted. Thus, in accordance with the invention a person need only to stand either barefoot or in his stocking feet upon the base or support with his feet in proper relation to the reticulated areas formed by the shadow lines of standard shoe measurements cast on the fluorescent screen by the rows of impermeable members under the action of X-rays to indicate not only the size of foot being measured but also the correct size of shoe for those particular feet. After trying on a shoe of the size corresponding to the preliminary foot and shoe measurements, the person wearing such a shoe then may check the correctness of the fitting by again standing on the supporting surface in the field of the X-rays and over the reticulated area and thus observe by means of the shadows cast by the indicator markers 26, 27 and 28 whether the extreme positions of the borders of the foot in weight bearing coincide or match with the particular shadow lines of the reticulated image pattern on the screen previously determined as being the real size and width of shoe which the feet should take.

The foregoing description is directed solely towards the construction illustrated, but I desire it to be understood that I reserve the privilege of resorting to all the mechanical changes to 5 which the device is susceptible, the invention being defined and limited only by the terms of the appended claims.

I claim:

1. In a shoe fitting and foot measuring apparatus, the combination with a source of X-rays and a fluorescent screen, of a support for a foot interposed between said X-ray source and the fluorescent screen, said support having a suitable foot receiving surface adapted for a person to stand on and permeable to X-rays, and means opaque to X-rays between said screen and said source of X-rays, said means being of such a character as to provide a plurality of spaced dense linear areas in the path of the rays and being so arranged that the shadows cast thereby on the fluorescent screen will form intersecting rows of shadow lines the spacings between which correspond with the usual length and width distances of recognized standards of 10 foot and shoe measurements whereby the extreme lateral and longitudinal dimensions of the foot to and including the outer limits of the superficial tissue surrounding the foot structure at these locations may be located and measured 15 for determining correct shoe fitting.
2. In a shoe fitting and foot measuring apparatus, the combination with a source of X-rays and a fluorescent screen, of a support for a foot interposed between said X-ray source and the fluorescent screen, said support having a suitable foot receiving surface adapted for a person to stand on and permeable to X-rays, and means opaque to X-rays carried by said support and disposed below the foot supporting surface thereof, said means being arranged in the line of vision between said screen and said source of X-rays, said means being of such a character as to provide a plurality of spaced dense linear areas in the path of the rays and being so arranged that the shadows cast thereby on the fluorescent screen will form intersecting rows of shadow lines the spacings between which correspond with the usual length and width distances of 20 recognized standards of foot and shoe measurements whereby the extreme lateral and longitudinal displacements of the foot in relation to a shoe and to and including the outer limits of superficial tissue surrounding the foot structure at these locations may be located and measured 25 for determining correct shoe fitting.
3. In a shoe fitting apparatus comprising a support having a foot receiving surface permeable to Roentgen or X-rays, a Roentgen or X-ray tube, an image receiving member, means carried by said support and beneath the foot receiving surface thereof for locating and measuring the extreme lateral and longitudinal displacement of the foot relative to a shoe under observation in the line of vision, said measuring means comprising two groups of rows of long narrow spaced 30 elements composed of a material opaque to X-rays and arranged in the field of the beam of the rays, the elements of one group being disposed at a right angle to those of the other group so that the shadows cast thereby on the image receiving member will be of a retiform character in which the spacing between the shadow lines of the respective groups corresponds with the usual length and width distances of 35 recognized standards of foot and shoe measurements.

and means opaque to X-rays and cooperating with said measuring means to provide reference lines relative to which said measurements are made.

4. In a shoe fitting apparatus, the combination 5 with a source of X-rays, and a fluorescent screen, of a support for a foot, a central longitudinally extending partition thereon, said partition being provided with transverse flange portions the outer longitudinal side edges of which form datum 10 lines for each foot and from which the width of foot is measured, a plurality of rows of longitudinally extending slender measuring elements arranged at fixed distances from the outer edges of said flanges and corresponding to the usual 15 width distances of recognized standards of foot and shoe measurements, a transverse heel member disposed at right angles to said partition and in an upright position, the inner face of said heel member serving to form a datum line from 20 which the length measurements of a foot or feet are determined and providing a right angle corner with the outer edges of said flanges for receiving the heel of the foot or the shoe, and a plurality of rows of slender transverse measuring elements arranged at fixed distances from the inner edge of said heel member and corresponding to the usual length distances of recognized standards of foot and shoe measurements, wherein the extreme width and length displacements of a foot and shoe will be located and 25 measured.

5. In a shoe fitting and foot measuring apparatus, the combination with a source of X-rays, and a fluorescent screen, of a support for a foot, 30 a central longitudinally extending partition fixed on said support, said partition being provided with transverse flange portions the outer longitudinal side edges of which form datum lines for each foot and from which the width of foot 35 is measured, a plurality of rows of longitudinally extending slender measuring elements arranged at fixed distances from the outer edges of said flanges and corresponding to the usual width distances of recognized standards of foot and shoe 40 measurements, a movable transverse heel engaging member adapted to be positioned at right angles to said fixed partition in an upright position, the inner face of said heel member when 45 so positioned serving to form a datum line from which the length measurements of a foot or feet are determined and providing a right angle corner with the outer edges of said flanges for receiving the heel of the foot or the shoe, and a plurality of rows of slender transverse measuring elements 50 arranged at fixed distances from the inner edge of said heel member and corresponding to the usual length distances of recognized standards of foot and shoe 55 measurements, wherein the extreme width and length displacements of a foot in relation to a shoe will be located and measured.

6. In a shoe fitting apparatus, the combination with a source of X-rays, and a fluorescent screen, of a support for a foot, a central longitudinally extending partition thereon, said partition being 60 provided with transverse flange portions the outer longitudinal side edges of which form datum lines for each foot and from which the width of foot is measured, a plurality of rows of longitudinally extending slender measuring elements arranged at fixed distances from the outer edges of said flanges and corresponding to the usual width distances of recognized standards of foot and shoe 65 measurements, a transverse heel member disposed at right angles to said partition and in an 70

upright position, the inner face of said heel member serving to form a datum line from which the length measurements of a foot or feet are determined and providing a right angle corner with the outer edges of said flanges for receiving the heel of the foot or the shoe, and a plurality of rows of slender transverse measuring elements arranged at fixed distances from the inner edge of said heel member and corresponding to the usual length distances of recognized standards of foot and shoe measurements, wherein the extreme width and length displacements of a foot and shoe will be located and measured, said outer edges of said flanged transverse portions being composed of a material opaque to X-rays and providing an abutment for the inner margins of the foot and shoe.

7. In a shoe fitting apparatus, the combination with a source of X-rays, a fluorescent screen, and a shoe having a pair of opposed index markers opaque to X-rays and carried by the shoe upper above the sole at the first and fifth metatarsophalangeal joints of the foot, of a support for a foot, a central longitudinally extending partition thereon, said partition being provided with transverse flange portions the outer longitudinal side edges of which form datum lines for each foot and from which the width of foot is measured, a plurality of rows of longitudinally extending slender measuring elements arranged at fixed distances from the outer edges of said flanges and corresponding to the usual width distances of recognized standards of foot and shoe measurements, a transverse heel member disposed at right angles to said partition and in an upright position, the inner face of said heel member serving to form a datum line from which the length measurements of a foot or feet are determined and providing a right angle corner with the outer edges of said flanges for receiving the heel of the foot or the shoe, and a plurality of rows of slender transverse measuring elements arranged at fixed distances from the inner edge of said heel member and corresponding to the usual length distances of recognized standards of foot and shoe measurements, wherein the extreme width and length displacements of a foot and shoe will be located and measured, the extreme lateral displacement of said index markers in the shoe upper being accurately located and measured by matching with fixed shadow lines cast by the rows of slender measuring elements on the screen by the action of X-rays.

8. In a shoe fitting and foot measuring apparatus, in combination, a support having a foot receiving surface permeable to Roentgen or X-rays, a Roentgen or X-ray tube beneath said support, a fluorescent screen spaced above said support, and means in position for observation by a person standing upon said support with the feet between the support and the screen for locating and measuring the extreme lateral and longitudinal displacement of the foot relative to a shoe, said measuring means comprising two groups of rows of long narrow spaced elements composed of a material opaque to X-rays and arranged in the field of the beam of the rays, the elements of one group being disposed at a right angle to those of the other group so that the shadows cast thereby on the fluorescent screen will be of a generally reticulated pattern in which the spacing between the shadow lines of the respective groups corresponds with the usual length and width distances of recognized standards of foot and shoe measurements, and means associated with said sup-

port and said groups of measuring elements adapted to provide reference or base lines relative to which said measurements are made and of a character as to cast a visible shadow on the image-receiving member.

9. In a shoe fitting and foot measuring apparatus, the combination with a source of X-rays, a fluorescent screen, and a shoe provided with an index marker opaque to X-rays, of a device between said screen and said source of X-rays in position for use in visually determining and measuring by means of shadow images cast on the screen by X-rays the extreme width and length size measurements of a foot and the relation of the shoe to the foot for correct shoe fitting and foot measuring, said device comprising a foot support on which a person is to stand while being measured for correct shoe fitting and made of a material permeable to X-rays, means associated with said support comprising two intersecting sets of parallel spaced members made of a material opaque to X-rays, one set being disposed at right angles to the other, the spacing of the respective sets of said members corresponding to the usual length and width distances of recognized standards of foot and shoe measurements, and means associated with said support and arranged so as to provide a longitudinal and a lateral surface at right angles to one another adapted to form datum lines from which the extreme length and width of a foot or shoe will be located and measured, when the heel of the foot or the shoe at the heel level and the inside marginal portion of the foot or shoe, on the big toe side, are held snugly in contact against said side surfaces of said partition means, the position of the opaque marker in the shoe being located and measured by the adjacency of its image to one of the series of shadow images cast on the screen by the parallel opaque members of said support under the action of X-rays.

10. A device adapted for use in visually determining foot size measurements under the action of X-rays comprising a support for a foot and made of a material readily permeable to X-rays and having a floor surface on which a person is to stand, means extending upwardly from the floor surface of said support and provided with opposite side face portions made of a material opaque to X-rays and adapted for engagement with the inner marginal sides of the foot and heel when the foot, with or without a shoe, is placed in a proper size measuring position, heel engaging means adapted to extend upwardly from the floor of said support and provided with a side portion made of a material opaque to X-rays and disposed laterally of the support so that the line of contact with the foot will be substantially at right angles to that of the side portions of said first named means to provide a generally right angle corner for the reception of the heels of the feet, and size measuring means made of a material opaque to X-rays and disposed on said support in a predetermined spaced arrangement from the respective foot and heel engaging portions of the first named and second named means, the spacing of said measuring means corresponding to the usual length and width distances of recognized standards of foot and shoe measurements.

11. A device for use in a shoe fitting and foot measuring apparatus for visually determining foot size measurements by means of shadow images cast on a fluorescent screen by X-rays, comprising a foot support member made of a material readily permeable to X-rays, a longitudinally

extending upright partition thereon, the opposite longitudinal side faces of which are of a character as to cast a visible shadow upon a fluorescent screen by the action of X-rays and form datum lines for each foot from which the width of foot is measured, a plurality of rows of longitudinally extending slender measuring elements associated with said support and arranged at opposite sides of said partition at fixed distances from said longitudinal side faces of the partition, the spacing between said measuring elements corresponding to the usual width distances of recognized standards of foot and shoe measurements, a transverse heel member disposed at right angles to said partition and positionable in an upright position, the inner face of said heel member being of a character capable of casting a visible shadow upon a screen by the action of X-rays, the inner face of said heel member serving to form a datum line from which the length measurements of a foot or feet are determined and providing a right angle corner for the reception of the heel of the foot or shoe at the heel level, and a plurality of rows of laterally extending slender measuring elements arranged at fixed distances from the inner side face of said heel member and corresponding to the usual length distances of recognized standards of foot and shoe measurements, wherein the extreme width and length displacements of a foot with or without a shoe, will be located and measured for correct shoe fitting.

12. A device adapted for use in visually determining foot size measurements by means of shadow images cast on an image receiving member by X-rays, comprising a foot support member made of a material readily permeable to X-rays, partition means extending upwardly from the top surface of said member and adapted to divide the same into a plurality of foot receiving floor sections upon which a person will stand while the feet are being measured for correct shoe fitting, means extending transversely of said support and disposed at right angles to said partition and adapted to form with a pair of side faces of the latter a right angle corner for the reception of the heel of each foot or shoe, and measuring means incorporated within the foot support member comprising a plurality of intersecting rows of spaced parallel wires arranged to form a generally reticulated pattern and made of a material opaque to X-rays, the spacing between said measuring elements corresponding to the usual length and width distances of recognized standards of foot and shoe measurements wherein the extreme width and length dimensions of a foot, with or without a shoe, will be located and measured with reference to said partition means and said heel engaging means.

13. A device for use in a shoe fitting and foot measuring apparatus for visually determining foot size measurements by means of shadow images cast on a fluorescent screen by X-rays, comprising a foot support member made of a material readily permeable to X-rays, partition means extending upwardly from the top surface of said member and adapted to divide the same into a plurality of foot receiving floor sections upon which a person will stand while the feet are being measured for correct shoe fitting, means extending transversely of said support and disposed at right angles to said partition and adapted to form with a pair of side faces of the latter a right

angle corner for the reception of the heel of each foot or shoe, and measuring means incorporated within the foot support member comprising a plurality of intersecting rows of spaced parallel wires arranged to form a generally reticulated pattern and made of a material opaque to X-rays, the spacing between said measuring elements corresponding to the usual length and width distances of recognized standards of foot and shoe measurements wherein the extreme width and length dimensions of a foot, with or without a shoe, will be located and measured with reference to said partition means and said heel engaging means, said partition means having flange portions extending from opposite side faces and being positioned at a distance above said foot receiving floor sections to contact with the inner marginal sides of a foot or shoe and adapted to form datum lines visible on the screen by X-rays from which said width measurements are made. 10

14. An X-ray apparatus for use in visually determining foot measurements for fitting shoes, comprising the combination of a foot support permeable to X-rays and forming a platform on which a person may stand with one or both feet to be measured when in body weight bearing position, an X-ray tube positioned at one side of such foot and arranged to direct its rays through the same, a fluorescent screen disposed at the opposite side of such foot in a position spaced from said X-ray tube and in the path of such rays, and means opaque to X-rays positioned in the path of such rays for casting an image on the screen for observation and visual determination of foot measurements, said means being so constructed and arranged as to cast on said screen a plurality of sets of intersecting spaced shadow lines, the spacings between said lines being such as to provide a system of coordinates whereby the extreme width of the foot and the difference in length positions of the distal ends of the metatarsal bones from the first to the fifth joints inclusive may be located and measured for determining their relative positions and the amount of inclination of the area of body weight bearing that they form across the ball of the functioning foot for correct shoe size of the foot. 30

15. In a shoe fitting and foot measuring apparatus, the combination with a source of X-rays and a fluorescent screen in spaced relation thereto in the path of such rays, of a support for a foot arranged between said source of X-rays and said fluorescent screen, said foot support being permeable to X-rays and forming a platform on which a person may stand with one or both feet to be measured when in body weight bearing position, and means opaque to X-rays and part of said foot support, said means being so constructed and arranged as to provide a reticulated arrangement of dense linear areas in the path of the X-rays so that the shadows cast thereby on the fluorescent screen will form intersecting rows of shadow lines, the spacings of which will correspond with the usual length and width distances of recognized standards of foot and shoe measurements whereby the extreme width of the foot, the relative longitudinal positions of the distal ends of the metatarsal bones and the difference in their length at the ball of the foot when in body weight bearing position may be shown and measured for determining correct shoe fitting. 60
